UNITED STATES PATENT OFFICE.

ARTHUR L. PROUT AND ADRAIN R. REYNOLDS, OF LONG BEACH, CALIFORNIA.

STEAM AND WATER SEPARATOR.

Application filed June 19, 1924. Serial No. 720,914.

To all whom it may concern:

Be it known that we, ARTHUR L. PROUT and ADRAIN R. REYNOLDS, citizens of the United States, residing at Long Beach, in the county of Los Angeles and State of California, have invented new and useful Improvements in Steam and Water Separators, of which the following is a specification.

This invention is a steam and water separator and consists of the novel features herein shown, described and claimed.

An object is to make an improvement over an ordinary steam trap and which will more effectually separate the water from the steam, as required to feed dry steam to an engine or the like.

Another object is to make a device of the class described, which may be readily adjusted for various steam pressures.

Another object is to make a device of the class described having means for indicating a leak in the float.

Another object is to make a steam and water separator for engines and the like which will carry lubrication to the steam chamber.

Other objects and advantages will appear from the drawings and specification.

The drawings illustrate a steam and water separator and lubricator embodying the principles of the invention.

Figure 1 is a vertical diametrical sectional elevation of the steam and water separator.

Fig. 2 is a view analogous to Fig. 1 and showing a modified construction.

Fig. 3 is a view in elevation of the steam and water separator and the lubricator, the view being taken looking in the direction indicated by the arrow 3 in Fig. 4.

Fig. 4 is a top plan view as indicated by the arrow 4 in Fig. 3, parts being broken away and shown in section.

Fig. 5 is a horizontal sectional detail on the lines 5—5 of Figs. 1 and 3 and looking downwardly as indicated by the arrows.

The details of construction and operation shown in the drawings are as follows:

A cylinder 1 has an outturned flange 2 at its upper end, an inlet nipple 3 below the flange 2 at one side and an outlet nipple 4 below the flange 2 diametrically opposite the nipple 3 and the lower end of the cylinder 1 has a tapered portion 5 leading down to a nipple 6 welded to the lower end of the tapered portion. A plug 7 is screwed upwardly into the nipple 6 and has a spider

8 across its center and a valve seat 9 at its upper end. The outlet pipe 10 is screwed into the lower end of the plug 7. The valve 11 has a head fitting upon the seat 9 and a stem 12 sliding through the spider 7. A ball 13 is formed upon the upper end of the valve stem above the head 11 and fits in a ball socket 14 upon the lower end of the float stem 15. The float stem 15 has a hollow 16 extending upwardly from the socket 14 to the upper end of the stem. The float 17 is fixed upon the lower half of the stem 15, there being perforations 18 in the stem 15 within the float 17 so that if steam leaks into the float 17 it will blow out of the top of the stem and indicate that the float is leaking. A cap 19 fits upon the upper end of the cylinder 1 and is secured to the flanges 2 by bolts 20 and the stem 15 is slidably mounted through the cap 19 and through a stuffing box 21 constructed upon the cap 19. A cross bar 22 fits upon the upper end of the stem 15 above the stuffing box 21 and a nut 23 is screwed down upon the stem against the cross bar 22. Posts 24 and 25 extend upwardly from the cap 19 through springs 26 and 27 and then through the cross bar 22 so that by adjusting the nut 23 the tensions of the springs 26 and 27 are adjusted to properly support the cross bar 22 and support the valve 11 with proper tension and the nut 23 may be readjusted for various steam pressures.

A cylinder 28 extends downwardly from the cap 19 and is spaced from the cylinder 1 to form a circulating chamber 29 outside of the cylinder, and a spiral baffle 30 is mounted around the cylinder 28 in the chamber 29. An inlet port 31 is formed through the cylinder 28 near its upper end and directly opposite the inlet nipple 3, and an outlet port 32 is formed through the cylinder 28 near the bottom 33, and ports 34 are formed through the bottom. A baffle or casting 35 extends downwardly from the cap 19 around the stem 15 to keep the stem from overheating. The bottom 33 is a sufficient distance above the top of the float 17 to allow the float to raise to open the valve 11. Water 36 extracted from the steam coming through the inlet nipple 3 and circulating around and through the parts in the upper part of the cylinder 1 will fill the bottom of the cylinder 1 until the buoyancy of the water is sufficient to raise the float 17 and open the valve 11, and when the water runs out

through the pipe 10 to a sufficient extent, the float 17 will go down and close the valve 11. The steam pipe from a boiler is to be connected to the nipple 3 and the dewatered steam will pass through the nipple 4 which is to be connected to an engine cylinder or the like.

In the modification shown in Fig. 2, the angle iron baffles 37 may be secured to the inner face of the cylinder 1 instead of the coil baffle 30 mounted upon the cylinder 28. The specific form of baffle is immaterial.

The cylinder 1 is mounted upon the legs 38 and is adapted to maintain an upright position.

Referring to Figs. 3 and 4, the small tank 39 is adapted to be mounted upon the outside of the cylinder 1 by straps 40 and 41. A branch steam pipe 42 leads from the nipple 3 to and through the top of the tank 39 and to near the bottom of the inside of the tank. A pipe 44, including a needle valve 45, an outlet check valve 46, and a sight feed gauge 47, is connected through the top of the tank 39 and connected in the nipple 4 so that steam pressure going through the pipe 42 will be discharged to the bottom of the stock 48 of lubricant and the steam will bubble up through the lubricant and become saturated with lubricant and pass into the nipple 4 to be carried by the dewatered steam to the engine cylinder or the like. The flow of lubricant may be accurately adjusted by watching the gauge 47 and manipulating the needle valve 45.

The upper ends of the posts 24 and 25 are screw threaded. Stop nuts 24' and 25' are mounted upon the screw threads. A second cross bar 22 is mounted upon the posts 40 against the nuts 24' and 25' and clamping nuts 24^a and 24^b are screwed down upon the posts 24 and 25 against the cross bar 22'. The cross bar 22' fits across the upper end of the stem 15 and is adjustably spaced therefrom to limit the upward movement or opening of the valve 11 and to limit the upward movement of the float 17.

Various changes may be made without departing from the spirit of the invention as claimed.

We claim:

1. A steam and water separator comprising a cylinder vertically mounted and having an inlet nipple near the top at one side and an outlet nipple near the top at the other side, a cap closing the upper end of the cylinder, means mounted in the upper part of the cylinder adapted to separate the water from steam passing in at one nipple and out at the other, a valve at the bottom of the cylinder, a stem extending upwardly from the valve through the cap, a float upon the stem in the lower part of the cylinder, the stem being hollow and there being perforations within the float leading to the

hollow so that steam or water in the float may blow out of the upper end of the stem.

2. A steam and water separator comprising a closed cylinder, an outlet valve at the bottom of the cylinder, a stem extending upwardly from the outlet valve, a float upon the stem for operating the valve, the stem extending slidingly through the top of the cylinder, a cross head adjustably mounted upon the stem, and springs supporting the cross head so as to adjust the valves to operate under different steam pressures.

3. A steam and water separator comprising a cylinder vertically mounted and closed at the bottom, an outlet valve at the bottom of the cylinder, a stem extending upwardly from the valve through a cap at the top of the cylinder, a float upon the stem in the lower part of the cylinder, a stuffing box around the stem at the top of the cylinder, posts extending upwardly from the top of the cylinder, springs upon the posts, a cross head resting upon the springs, the stem extending through the cross head, and a nut upon the stem against the cross head so as to adjust the valve to operate at different steam pressures.

4. A steam and water separator comprising a vertical outer cylinder, an inlet passage upon one side of the cylinder adjacent the top thereof, an outlet passage in another side of the cylinder adjacent the top thereof, an inner cylinder disposed within said outer cylinder having an inlet passage registering with the inlet passage to the outer cylinder and an outlet passage formed adjacent its bottom, and means for withdrawing water collected in the bottom of said outer cylinder.

5. A steam and water separator comprising a vertical outer cylinder, an inlet passage upon one side of the cylinder adjacent the top thereof, an outlet passage in another side of the cylinder adjacent the top thereof, an inner cylinder disposed within said outer cylinder having an inlet passage registering with the inlet passage to the outer cylinder and an outlet passage formed adjacent its bottom, and a float operated valve for withdrawing water collected in said outer cylinder.

6. A steam and water separator comprising a vertical outer cylinder, an inlet passage upon one side of the cylinder adjacent the top thereof, an outlet passage in another side of the cylinder adjacent the top thereof, an inner cylinder disposed within said outer cylinder having an inlet passage registering with the inlet passage to the outer cylinder and an outlet passage formed adjacent its bottom, a port formed in the bottom of said inner cylinder, means forming a helical baffle between said cylinders, and means for withdrawing water collected in the bottom of said outer cylinder.

7. A steam and water separator comprising an outer receptacle, an inner receptacle disposed therein, inlet ports formed in said inner and outer receptacles registering with each other, an outlet port formed in said outer receptacle adjacent the top thereof, an outlet port formed in said inner receptacle adjacent the bottom thereof, and means for removing water collected in the bottom of said outer receptacle.
8. A steam and water separator comprising an outer receptacle, an inner receptacle disposed therein, inlet ports formed in said inner and outer receptacles registering with each other, an outlet port formed in said outer receptacle adjacent the top thereof, an outlet port formed in said inner receptacle adjacent the bottom thereof, means
- forming a helical baffle between said inner and outer receptacles, and means for withdrawing water collected in the bottom of said outer receptacle. 20
9. In a steam and water separator having a receptacle in which water separated from the steam is adapted to be collected, a valve 25 permitting removal of the water from said receptacle, a stem secured to said valve, a float mounted upon said stem, spring means supporting said stem, and means for adjusting said stem upon said spring means 30 as and for the purpose described.

In testimony whereof we have signed our names to this specification.

ARTHUR L. PROUT.
ADRAIN R. REYNOLDS.
